PROTECTED BLADE AND PACKAGE

Joseph Muros, Cambridge, Mass., assignor to
Gillette Safety Razor Company, Boston, Mass.,
a corporation of Delaware

Application April 6, 1944, Serial No. 529,752

3 Claims. (Cl. 206—46)

1

This invention relates to the protecting and packaging of thin-edged blades, such as safety razor blades, between the stages of manufacture and use.

In handling safety razor blades under commercial conditions of transportation and distribution and in the more or less casual treatment of such blades by the user, the extremely fine keen edge of the blade is likely to become dulled by being brought into contact with its wrapping or with other objects before it can be actually clamped in shaving position in the razor. On this account the best and most skillful efforts of the manufacturer in sharpening blades are often brought to naught because of the damage done to the very fragile and delicate structure of the blade edge after it has been brought to the keenest possible shaving condition and before the shaving operation is actually undertaken.

An important field of use for my invention is in connection with open-end blades, that is to say, blades having a longitudinal medial slot opening through one unsharpened end of the blade. Such blades are adapted for use in safety razors wherein the cap and guard members are connected for only limited separation to receive a blade presented edgewise between them, as well as in safety razors in which the cap and guard members may be entirely detached from each other.

The present invention is applicable to open-end blades and permits the user to insert the protected blade in shaving position between the slightly separated cap and guard members and then to strip the protective cover from the blade by pulling it endwise while the blade remains in its shaving position.

The present invention deals with blades of a type which it is desired to protect at the time and place of manufacture by enclosing them in a wrapper or envelope. The wrapper overlaps and safeguards the sharp edge or edges of the razor blade and must be removed eventually to make the blade edge accessible for shaving. It has sometimes happened that in stripping the wrapper or envelope from a blade already positioned in a razor the envelope has become entangled with the razor and has been torn, leaving a portion of it in the razor instead of being withdrawn intact. Such an occurrence is an annoyance to the user because the torn portion of the wrapper must be extracted from the razor before it can be satisfactorily organized for shaving and this not only delays the user but it introduces a risk of cutting his fingers. With these conditions in view an important feature of the present inven-

2

tion consists in a razor blade protected by an envelope or wrapper having extended portions or wings which project outwardly from the blade beyond or between any part of the razor that might otherwise obstruct free removal of the wrapper. Going more into detail, the present invention contemplates providing the blade envelope with wings which extend forwardly beyond the end of the cap and guard members of the razor, these wings serving as guides to direct the body of the wrapper and prevent it from catching when it is pulled endwise out from between the cap and guard members.

The invention includes within its scope a new and improved package of protected blades of the character above described. It is desirable to secure the protected blades in stack formation within the package in which they are dispensed and to hold the individual blades in position against shifting while the package is being transported or handled after it leaves the place of manufacture. This is important because otherwise the keen, sharp edge of the razor may work itself into contact with the folds of the wrapper and thus lose its original keenness.

With these conditions in view an important feature of the invention consists in a blade package including in its organization a supporting frame of sheet material having cooperating ears or lugs constructed and arranged to engage the shouldered protected blades of a stack in such a manner as to prevent their longitudinal or transverse shifting and at the same time providing within the package adequate space for projecting wings on the wrapper or envelope.

These and other features of the invention will be best understood and appreciated from the following description of a preferred embodiment thereof, selected for purposes of illustration and shown in the accompanying drawing in which:

Fig. 1 is a view in perspective on an enlarged scale of a partially opened blade package;

Fig. 2 is a view in perspective of a safety razor head, part of the cap being broken away to show portions of a protected blade;

Fig. 3 is a plan view of the razor head and blade as seen from beneath; and

Fig. 4 is a view in cross-section on the line 4—4 of Fig. 1.

The invention is shown in its application to a double-edged open-end blade of the "Gillette" type, although it will be understood that it is not limited in its application to this or to any other specific type of blade. As shown in Fig. 1, however, the blade 10, which is formed of sheet

steel between .003 and .007 inch in thickness, has a central longitudinal slot 11 and reentrant recesses in each of its corners, which define elongated unsharpened portions 12 at both ends of the blade. Each individual blade is protected by a wrapper 13 comprising upper and lower elongate leaves extending slightly beyond the cutting edges of the blade and including tongues 14 and 15 at opposite ends which overlie the elongated end portions of the blade. The two leaves of the wrapper are connected and folded over the shoulders of the blade at its open end on both sides of the elongated end portion of the blade and at both sides of the tongue 15. The wrapper has also ears 16 at one end which are folded transversely over the tongue 14 and the enclosed end portion of the blade. The upper and lower leaves of the wrapper 13 are cut away internally fully to expose the slot 11 of the protected blade.

In Fig. 1 four blades 10 are shown in superposed stacked relation with the open end of each blade directed rearwardly or toward the left. At the opposite or closed end of the blades both leaves of each wrapper are provided with forwardly extending wing portions 17. These wings are flush at their outer edges with the outer edges of the leaves of the blade wrapper 13 and are curved inwardly and rearwardly at their forward ends forming a deep valley or notch in the contour of the blade wrapper.

In Fig. 1 the four blades are shown as assembled between the pasteboard or fibre covers 18 and 19 of a blade package, all being held together by a staple 20 which passes through the rearwardly extending tongues 15 of the blade wrappers. The package includes in its structure a thin metal plate or sheet 21 which is crimped at its longitudinal edges over the side edges of the lower package cover 19, extending across the same from side to side beneath the blade stack. At both sides of its rear end the plate 21 is transversely slotted and its material folded upwardly to form a pair of upstanding folded ears 22 spaced apart to engage the shoulders of the elongated end portion of the blade 10 at its open end. At its forward end the plate 21 is also slotted and its material bent up to provide a pair of upstanding ears 23 and also a pair of folded ears 24. Both these pairs are spaced apart to engage and position the covered forward solid ends 12 of the blades and the upright ears 23 fit snugly into the valleys at the base of the wings 17. The upright ears 23 and the folded ears 22 embrace between them the bodies of the stacked blades and therefore hold them positively against longitudinal displacement. The double ear arrangement at the forward end of the plate 21 is desirable on account of the specific shape of the forward end of the blade wrapper 13 due to its extension wings 17. The upright ears 23 fit into the slots defining these wings where the folded ears would not pass.

Normally the blade package is closed by a folded end portion which is represented in Fig. 1 as having been torn off to make the blades accessible. The cover 18 is shown as partly lifted and the individual blades may be removed one by one from the package by swinging them up above the ears 22-23-24, and then tearing them away from the staple 20.

The manner of using a protected blade in connection with a safety razor having connected cap and guard members is shown in Figs. 2 and 3. The razor therein shown comprises a handle 25, a guard member 26 and a cap member 27. The

guard member is provided with parallel fulcrum shoulders over which the blade is flexed by the cap 27 and the two blade clamping members are drawn together by threaded connection 5 of the cap 27 with the handle 25. The cap is shown as provided with reinforcing corner lugs and a pair of aligned blade-locating ribs 28 which pass through clearance notches in the bottom of the guard member 26 as shown in Fig. 3.

In practice, a protected blade may be inserted endwise between the cap 27 and the guard 26 while these two members are disengaged and separated sufficiently to afford a blade passage as shown in U. S. Letters Patent No. 2,342,160, granted Feb. 22, 1944, to the applicant herein jointly with Nicholas Testi. The protected blade may be moved fully into shaving position in the razor since its open-end longitudinal slot 11 permits it freely to pass the blade-locating ribs 28, or the blade may be placed directly on the cap and the parts then assembled. The protected blade is then held in shaving position by exerting yielding pressure upon the cap and guard members and the protective cover is removed by grasping the projecting end which encloses the tongue 14 and pulling the wrapper outwardly while the blade itself is held against displacement by the ribs 28 and the stem of the cap. It will be noted that the wings 17 extend outwardly from beneath the corners of the razor head with the result that the protective cover may be stripped completely and cleanly from the blade and removed from the razor head without damage and without leaving any fragments thereof in places where they will obstruct the shaving operation. Having completely stripped and removed the protective cover the blade-clamping operation may be completed upon the bare blade and the razor thus made ready for the shaving operation.

Having thus described my invention, I claim as new and desire to secure by Letters Patent:

1. A safety razor blade centrally slotted and having shoulders defining unsharpened end portions in the blade, in combination with a protecting wrapper having elongate leaves folded transversely upon said shoulders at one end of the blade and slotted to expose the slot of the blade, the leaves of the wrapper being wrapped about the other end portion thus holding the blade against transverse displacement in its wrapper, and wings on the wrapper extending forwardly beyond the shoulders at either side of the wrapped end portion of the blade and thereby serving as guides to direct the body of the wrapper and prevent it from catching when pulled endwise out of a razor.

2. In a blade package having a flat sheet with spaced upstanding blade-locating ears and adjacent folded ears therein; a protected blade disposed between the ears of the package and having a flexible wrapper covering the body of the blade between said ears and wings projecting outwardly at one end of the wrapper beyond said upstanding ears.

3. A package of protected blades including cooperating covers having upstanding ears presenting thin edges and adjacent folded ears located within the outline of the covers, and a stack of blades each having a wrapper with wings extending from one end thereof and spaced from the blade by notches in the wrapper in which the upstanding ears of the package cover are received.

JOSEPH MUROS.
